(57) **CLAIM**

The ornamental design for a car rim as shown and described.

DESCRIPTION

FIG. 1 is a front perspective view of a car rim;

FIG. 2 is a front elevation view thereof;

FIG. 3 is a side elevation view thereof;

FIG. 4 is a rear perspective view thereof;

FIG. 5 is an enlarged elevation view of FIG. 2; and,

FIG. 6 is an enlarged perspective view of FIG. 1.

The dashed broken lines showing portions of the car rim form no part of the claimed design. The dashed dot dashed broken lines depict boundary lines that form no part of the claimed design.
